UNITED STATES PATENT OFFICE.

SIDNEY R. BLANCHARD, OF OTTAWA, ILLINOIS.

COVERING FOR WALLS.

SPECIFICATION forming part of Letters Patent No. 629,100, dated July 18, 1899.

Application filed December 1, 1898. Serial No. 697,944. (No model.)

To all whom it may concern:

Be it known that I, SIDNEY R. BLANCHARD, of Ottawa, in the county of La Salle and State of Illinois, have invented certain new and useful Improvements in Coverings for Walls; and I do hereby declare that the following is a full, clear, and exact description thereof, reference being had to the accompanying drawings, and to the letters of reference marked thereon, which form a part of this specification.

This invention relates to an improved ornamental finish or covering for the ceiling and walls of rooms intended to simulate glazed bricks, tiles, or the like, which consists of a plurality of similar sections which are applied to the ceiling or walls with their margins in contact and in such manner as to form a continuous and connected covering.

The invention refers more specifically to the form and construction of such sections and to the means by which they are applied to the ceiling or wall.

The invention consists in the matters hereinafter set forth, and more particularly pointed out in the appended claims.

In the drawings, Figure 1 shows one section of one form of the covering. Fig. 2 illustrates the manner of joining the sections together and attaching the same to the wall. Fig. 3 is a detailed sectional view of the contiguous parts of two adjacent sections. Fig. 4 illustrates another form of covering which is adapted more particularly to be used as wainscoting. Fig. 5 illustrates the manner of joining the sections together shown in Fig. 4 and illustrates also the manner of applying a border thereto. Fig. 6 illustrates a section of the border shown in Fig. 5. Fig. 7 illustrates the manner of joining the contiguous sections of the border together.

A sectional covering made in accordance with my invention consists generally of a base-sheet of paper-board or the like which is covered with a plurality of small sections of enameled wood, pulp-board, or like material, which simulate tiling, and finished and arranged upon the base-sheet in a manner to imitate encaustic tiles. Each of said sections is constructed and arranged to overlap the continuous sections and to be joined thereto so that the sections when applied to the wall

or ceiling constitute in effect a single continuous covering.

The form of covering shown in Figs. 1, 2, and 3 may be applied either to a ceiling or wall, each of the sections consisting of a base-sheet A and a plurality of smaller sections B, hereinafter designated "tiles," which are applied to the outer side of said base-sheet and secured thereto by any suitable adhesive substance.

Said base-sheet A will desirably be made of paper or the like of such thickness as to give it the required stiffness to prevent its being easily bent or broken, and will be made of a size which will permit the same to be most advantageously applied. Said base-sheets are rectangular or may be made of other angular contour which will permit of the different sections being joined together at their margins without leaving intermediate spaces

between the adjacent sections. The tiles B are made of such shape and are so arranged upon the base-sheet that when applied to said sheet they form a practically-connected covering of the same shape and size as the base-sheet. Said tiles are so arranged upon the base-sheet of each section as to extend beyond or overlap said sheet at two sides thereof, as indicated in dotted lines in Fig.

1, while the base-sheets at the remaining sides of the section extend beyond the tiles, as clearly shown in said Figs. 1, 2, and 3. When the sections are applied to the wall or ceiling, they will be so arranged that the sides thereof in which the tiles overlap the base-

sheet will be joined to the sides of the adjacent sections in which the base-sheet projects beyond the tiles, so that said projecting parts of the tiles of one section will have overlapping engagement with the base-sheet of the adjacent sections, and vice versa, as clearly indicated in Figs. 2 and 3. A suitable adhesive substance will be applied between the overlapping parts of the adjacent sections, so

as to join the same together, and the projecting parts of the base-sheet and tiles of the opposite sides of the sections will be made of equal width, so that when said sections are joined together the outside rows of tiles of

two adjacent sections will occupy the same relation to each other as do the rows of tiles on each separate section, whereby the line of de-

marcation between said sections will not be visible. As shown in said figures, the tiles are rectangular and arranged on the base-sheet in straight parallel rows which extend in transverse directions. The shape and arrangement of said tiles may, however, be varied so long as the overlapping arrangement of the sections above described is preserved and the several tiles form a continuous covering for the base-sheet. Each section will be attached to the wall by means of screws or nails which pass through the base-sheet in the parts which project beyond the tiles. The parts of each section which overlap the base-sheet of the adjacent sections cover the heads of said screws or nails when placed in position upon the walls or ceiling. As an additional means for securing each section to the wall or ceiling, one or more tiles will desirably be omitted from the base-sheet when the sections are made up, as indicated at B' in Fig. 1, and the nails or screws will be driven through said sheet at these points, after which the tiles will be applied to or within such spaces and cover the nail or screw heads. It will be seen, therefore, that when the several sections have been applied to the wall or ceilings in the manner set forth the attaching means will be covered by the tiles and the lines of demarcation between the adjacent sections will not be visible, and the appearance to the eye will be that of an unbroken covering of tiles.

In Figs. 4 and 5 is shown a form of covering in which the tiles are arranged upon the base-sheet, and the adjacent sections are joined together in a manner different from that heretofore set forth. In said figures, C designates the base-sheet, and D the tiles attached thereto. Said tiles are of elongated rectangular form and are arranged upon the base-sheet in straight parallel lines in the direction of their length; but the joints between the adjacent ends are opposite the unbroken surfaces of the adjacent tiles, so that the tiles of adjacent rows break joints. Said tiles project over the edges of the base-sheet C at one of the edges, which is horizontal when the section is applied to a side wall, and the base-sheet projects beyond the tiles at the opposite margin of the section and is adapted to be overlapped by the projecting portions of the tiles D of the next adjacent section, said overlapping parts being secured together by a suitable adhesive substance. The arrangement of the tiles D upon the base-sheet is such that the end tile of each alternate row of tiles at the side or vertical edge of the base-sheet is flush at its outer end with the side of the sheet, while the end tiles of the intermediate rows are at a distance inwardly from the edge, thereby leaving spaces C' between said tiles of one-half the length of a tile at each side edge of the sheet. The tiles of the several sections are so arranged that when the sections are placed side by side the spaces C' come in position opposite each other and

form spaces partly in one and partly in the other section of the full size required for the reception of the tiles D, said tiles when inserted therein being attached one-half to the base-sheet of one of the sections and one-half to the base-sheet of the other section. By this means the sections are joined together and in such manner that the line of demarcation between the sections is not visible. The several sections will be attached to the wall by means of screws or nails c, which are inserted through the base-sheet in the spaces C' and in the part of said sheet which projects beyond the tiles at one side thereof, which screws or nails are covered by the inserted tiles in the one instance and by the overlapping tiles in the adjacent section in the other instance, as indicated in Fig. 5.

The two forms of covering heretofore described may be used wherever found convenient or desirable. The construction and appearance of the form shown in Figs. 4 and 5 render the same applicable for use on the vertical walls of a room next adjacent to the floor to simulate wainscoting. The form shown in Figs. 1, 2, and 3 will more commonly be used to cover the ceiling of a room or the vertical walls thereof above the wainscoting.

In Figs. 6 and 7 is shown a border which is adapted for use in connection with either or both forms of covering heretofore described. The said border is made, essentially, like the sectional coverings previously described, each section consisting of an elongated-rectangular base-sheet E and a plurality of tiles F, G, and G', attached to the outer side thereof. The tiles F, which are elongated rectangles, are arranged in two parallel rows, one on each side of the base-sheet, with an open space of uniform width between the same. The tiles G, which are equilateral rectangles, are arranged in the open spaces between the rows of tiles F with one of their diagonals perpendicular to said outer row of tiles, said tiles G being of such size as to extend entirely across the space between said outer rows when arranged in the position set forth. Between the adjacent sides of the tiles G and the inner sides of the tiles F are formed a number of isosceles-triangular spaces which are filled with like-shaped tiles G'. The base-sheet E is of such width as to extend beyond the tiles on both sides of the border, which sides are horizontal when the border is in position on the wall, said projecting parts of the base-sheet being adapted to have overlapping engagement with the overlapping parts of the tiles of the adjacent sections of the covering, as shown in Fig. 5, so that the tile-section of the border and those of the covering proper are brought into approximate contact with each other. The tiles F of each section are flush at their outer ends with the ends of the base-sheet. The equilateral-rectangular tiles G are so arranged with respect to said tiles F that an isosceles-triangular space is left at

each end of each section, so that when the sections are arranged end to end with two triangular spaces opposite each other said spaces form together an equilateral rectangle, 5 one-half in each adjacent section, within which one of the tiles G is adapted to be inserted and secured by any suitable adhesive substance. By this means the several sections of the border are joined together. Said 10 several sections are secured to the wall by means of nails or screws f inserted through the base-sheet in the spaces at the end thereof and which are covered by the inserted tiles G and also by nails or screws inserted through 15 the base-sheet in its part which extends beyond the tiles and which are covered by the overlapping parts of the tiles of the adjacent cover-sections. Said border will commonly be employed between the form of cover shown 20 in Figs. 4 and 5 when the same is used in imitation of wainscoting and the forms shown in Figs. 1 and 2 when employed as a covering for the wall above the wainscoting, but may be used wherever it is desirable to employ a 25 border.

Each of the tile-sections will desirably be made of a base of paper-board or like material which is sufficiently porous to permit the adhesive substance by which the tiles are secured to the base-sheet to readily penetrate the same and an outer covering of wood-pulp which is smoothly finished and glazed to simulate an encaustic tile. The construction of the tiles is shown in the sectional view, 35 Fig. 3. Said tile-sections are made of such hardness on their exterior surfaces as to resist the penetration of liquids, thereby permitting said tiles, when they have become soiled, to be cleansed by the application of 40 water. The exterior surface of the tiles may be colored to suit the taste of the designer.

The tiles of the sections described will not be placed in actual contact with each other, thereby leaving narrow spaces between the 45 same. Said spaces will be filled to the level of the outer surfaces of the tiles with a suitable plastic material which will, after exposure, become hardened, such as Portland cement, plaster-of-paris, or other suitable waterproof 50 cement. Said filling will be made of an adhesive substance, so that when it is dry it will serve to bind the tile-sections more firmly together, and will also be waterproof to prevent access of water to the base of the tile-sections 55 when being cleansed or at other times.

In case the ceiling be of such character that the sections employed to cover the same cannot be secured directly thereto, furring-strips may be first secured to the ceiling and arranged at such distances apart as to come opposite the parts of the base-sheet through 60 which the nails or screws are to be driven.

I claim as my invention—

1. As a new article of manufacture, a covering-section consisting of a base-sheet and a plurality of pieces simulating tiles which are attached edge to edge to the outer face of

said base-sheet, said pieces being so applied to said base-sheet that marginal parts thereof will be left uncovered, whereby when the 70 section is applied to the wall with the edges of its base-sheet in contact with the base-sheets of similar sections, the marginal parts of such base-sheet may be covered by pieces which overlap the joints between the base-sheets. 75

2. As a new article of manufacture, a covering-section consisting of a base-sheet and a plurality of pieces simulating tiles which are attached edge to edge to the outer face of said 80 base-sheet, said pieces being so applied to said base-sheet that the marginal parts thereof will be left uncovered whereby when the section is applied to the wall with the edges of its base-sheet in contact with the base-sheets of similar sections, the marginal parts of each base-sheet may be covered by pieces which overlap the joints between the base-sheet, and one or more of said pieces being omitted from the base-sheet to afford spaces 85 for the insertion of attaching screws or nails through said base-sheet. 90

3. As a new article of manufacture, a covering-section consisting of a base-sheet and a plurality of pieces simulating tiles which are 95 attached edge to edge to the outer face of said base-sheet, said pieces being so applied to said base-sheet that one or more of the margins of the latter will be left uncovered and said pieces will project beyond the base-sheet 100 at one or more margins of the latter.

4. As a new article of manufacture, a covering-section consisting of a base-sheet, and a plurality of pieces simulating tiles which are attached edge to edge to the outer face of said 105 base-sheet, but not in contact with each other, said pieces being so applied to said base-sheet that marginal parts thereof will be left uncovered, whereby when the section is applied to the wall with the edge of its base-sheet in contact with the base-sheets of similar sections, the marginal parts of each base-sheet may be covered by pieces which overlap the joints between the base-sheets, and a filling inserted 110 between the adjacent edges of said pieces and 115 flush with the outer surfaces thereof.

5. As a new article of manufacture, a covering-section consisting of a base-sheet, and a plurality of pieces simulating tiles which are attached edge to edge to the outer face 120 of said base-sheet, each of said pieces comprising a porous base which is attached to said base-sheet by adhesive material and a hard or glazed outer coating which is permanently joined to said porous base. 125

In testimony that I claim the foregoing as my invention I affix my signature, in presence of two witnesses, this 29th day of November, A. D. 1898.

SIDNEY R. BLANCHARD.
